STORAGE TANK

William E. Joor, Jr., Washington, D. C.

Application October 26, 1945, Serial No. 624,840

11 Claims. (Cl. 220—18)

1

This invention relates to improvements in storage tanks particularly those utilized for the storage of large quantities of volatile liquids such as motor fuels, aviation gasoline and other chemicals stored under their own vapour pressure substantially to prevent evaporation and leakage into the outside atmosphere.

An object of my invention is to provide a storage tank comprising a substantial annular foundation structure with which are securely incorporated supporting columns and frame work for the support and assembly of the general tank members.

Another object is to provide a tank having a side wall, curved outwardly from bottom to top and forming an extension of the convexed or curved roof with which, in larger sizes at least, is associated an inner or central column preferably of hollow construction.

Another object consists in providing a tank of the character described above in which the load of and that super-imposed upon the roof will be largely or wholly supported by the columns, such load in the larger sizes being shared by and received in part by an inner or central column.

Another object is to provide a tank of the character described in which the side walls and roof, and, if so desired, the bottom are constructed of plates curved in one direction only and secured together in leak-proof relation, as by welding, to permit the fabrication of the tank or container proper at the place of installation.

Another object is to provide a tank generally of the character described in which the roof and side plates are secured to a ring-shaped girder, as I term it, preferably at or closely adjacent to the neutral axes (vertical and horizontal) of such ring-shaped girder.

Other objects are exemplified in structural details described in the following specification illustrated in a specific embodiment of my invention as shown in the accompanying drawings, in which:

Fig. 1 is a side elevation of a storage tank embodying the novel features of my invention, a portion of the side wall being broken away to expose the central column and the attachment of the radial trusses thereto;

Fig. 1-A is a side elevation of a portion of a tank embodying a slightly modified form of a central column and illustrating the attachment of the top and bottom plates thereto;

Fig. 2 is a plan view of a portion of a tank embodying my invention, the roof plates being broken away for clarity;

2

Fig. 3 is a vertical section along the line 3—3 of Fig. 2;

Fig. 4 is a vertical section along the line 4—4 of Fig. 2;

5 Fig. 5 is a vertical section along the line 5—5 of Fig. 2;

Fig. 6 is a vertical section drawn to enlarged scale showing the assembly at the points of attachment of the roof plates, side plates, and ring-shaped girder.

Like numerals refer to like elements throughout the drawings in which A indicates generally the foundation structure, such foundation being mainly of concrete upon a horizontal extension

15 10a of the tank bottom 10. Vertical and horizontal bars 11 and 12 are located at intervals around the foundation as are vertical reinforcing rods 13 welded or otherwise secured to the bars 11. To increase the strength and rigidity of the foundation for a given amount of concrete, I provide hollow cores 14 as illustrated. The outer periphery of the concrete foundation is encased in the cylindrical plate-like housing 16.

20 I have illustrated the tank as provided with a curved bottom 10 which preferably is formed of a plurality of metal plates curved in one direction only, i. e., a section taken in a vertical plane through each plate will be curved but a section taken in a horizontal plane through the same

25 plate will be a straight line. The plates are preferably securely welded at their adjacent edges to preclude leakage of gas or liquid therebetween. Side plates 18 are attached at their lower edges, as by welding, to the casing 16 as illustrated for example in Fig. 3 and associated with them and secured to them at their point of juncture are horizontal angle bars 20 preferably embedded in the concrete foundation. It will be apparent that

30 this foundation can be poured and permitted to set before assembly of the remainder of the structure other than the vertical columns described below. The side plates are also curved in one direction only from top to bottom and are secured preferably by welding at their adjacent edges to form the complete side wall of convexed construction as illustrated in Fig. 1 for example.

35 Located above and spaced from the foundation A is what I term a ring-shaped girder generally designated by B, this being generally of I-section with an inner vertical flange 22 to which is secured by angles 22a, an annular web member 23. An outer vertical flange 25 is associated with the flange 22 as a part of this girder and the flange itself is preferably formed as a

40 45 vertical extension of the side wall 18 as illus-

trated in Fig. 3 for example. Projecting inwardly from the flange 25 is the annular web 26, secured to it as by welded gussets 27 and 28. Diagonal struts 24 extend between and are welded or otherwise secured to the webs 23 and 26 (see Fig. 2), in effect creating a trussed girder. A peripheral angle bar 29 is located at the top of the flange 25 and secured thereto; this likewise being secured to gussets 27. Gussets 28 are notched or cut away to permit their extension above the web 26 as illustrated. Inverted angle bars 31 are secured, as by welding, to the under face of flange 26 and similar, relatively inverted, angle bars 33 are secured, as by welding, to the upper face of the flange 26, these angles 31 and 33 preferably being located at or near a neutral axis of the ring-shaped girder B. A convex roof 35 is provided, this being formed of plates curved in one direction only and welded at their adjacent edges in such manner as to preclude leakage of gas or liquid. From the upper part of the side wall plates forming the side wall 18 are extension plates 37, secured, as by welding, adjacent the lower edge to the side wall plates and similarly secured to one arm of the angles 31 at the upper edges. The lower ends of the roof plates forming roof 35 are similarly secured as by welding one end to the angles 33. In large tanks I find it desirable to provide an inner or central support for the roof and supporting trusses and, in Fig. 1, I have illustrated a center column 40 comprising a hollow cylinder of substantial diameter. The plates forming the bottom 10 are curved upwardly to meet and to be secured, as by welding, to the base of the cylinder 40 at 40a and the plates forming the roof 35 are similarly curved downwardly to meet the upper end of the column 40 at 40b where they are secured, as by welding. In Fig. 1-A I have illustrated a variant of column 40 for which is substituted a column 40' which is composed of two conical frusta having their smaller ends welded together to form a unitary column to which the bottom and roof plates are secured in a manner similar to that in the form illustrated in Fig. 1 for example.

At intervals about the inner periphery of the tank are provided vertical columns C, formed in more or less conventional manner of outer upright members 49 illustrated as structural channels and inner vertical members 49 similarly of angle construction, the lower portion thereof being angularly and inwardly bent at 49a. The lower extremities of uprights 48 and 49 are likewise extended into the concrete foundation A. Struts 50 extend between and are secured to gussets 52 at their inner ends, said gussets being also secured to vertical members 49. At their outer ends the struts 50 are similarly secured to the gussets 28 and thereby to the upright members 48. The uppermost angular strut 50 of each column is secured on its upper end to the corresponding gussets 28 as illustrated.

Radial trusses generally indicated at D extend between the columns C and the central column 40, being secured at their inner ends to gussets 55 at such column as illustrated in Fig. 1. These trusses are of generally conventional construction including upper and lower angle bars 56, 57, the former comprising in effect rafters for the roof plates to whose contour they substantially conform. The lower bar 57 is bent at 57a and slightly bent at 57b (see Figs. 1 and 3). Struts 59 and 60 extend between the upper and lower bars 56, 57 being secured thereto by gussets 61, 62 and the outermost strut 59 of each truss D is secured to

the same gusset 62 to which is secured the upper end of the uprights 49. Similarly the outer ends of bars 57 are secured to gussets 49a completing the securing of the radial trusses to the columns 49. One of the vertical uprights 60 is secured to flange 22 of the ring girder (see Fig. 3).

Transverse tie members 79 are provided between the girder B and the column 40 near the under side of the roof plates and are secured to the rafters 56 at intervals by short struts 71, which are in turn secured to gussets 72, which are carried by said rafters. Between the cross ties 78 and the column 40 are similar tie members 75 which are secured in a similar manner to the rafter members 56 (see Fig. 2). Intermediate the columns C, about the inner periphery, of the tank are columns E which are substantially identical in construction with columns C save that the inner upright is not angularly formed as in the case of uprights 49. Otherwise the construction and arrangement is identical and needs no detailed explanation.

At intervals about the inner periphery of the tank wall and between columns C and E, angle bar struts 77 are secured to and project from the inner flange 22 of ring-shaped girder B. At their upper ends these struts 77 are secured to gussets 78 carried by the rafters 56 thereby providing additional support for the roof.

It will be apparent that with the construction described and illustrated substantially the entire weight of the roof plates and any load thereon is transmitted to the foundation through the columns and frame work and such roof plates are adequately supported between the center column 40 and the supporting columns C and E by the structure described above. This permits the use of relatively light plates and likewise permits the use of light material for the side plates which are relieved of load support.

Before pouring the concrete foundation ring, it is, of course, desirable to remove soil and loose over-burden to obtain a rigid base of rock or hard-pan and thereafter to spread a layer of sand which can be readily levelled off to afford a smooth support for the bottom plates.

With the curved roof and side wall structure, it will be apparent that pressure from the inside due to confined vapor or liquid will set up longitudinal stresses in the roof and side plates which, 50 being secured to the ring girders, preferably are adequately taken care of by the framework, including the foundation.

Since I am able to use relatively light plates for the roof and side, such plates may be readily cut and bent to desired form at the place of installation with simple, easily operated equipment and the plates likewise can be conveniently and economically welded to form a gas and liquid tight container. This permits me to dispense with a great part of the prefabrication in the shop which is necessary with present day structures and materially reduces the cost of the ultimate structure due to saving in labor, handling, freight, etc. Likewise this construction permits a more expeditious erection than might otherwise be possible.

It is to be noted that the ring-shaped girder B includes an integrated trussed construction comprising the plates 23, 26, and the struts 24. This arrangement permits the building of the girder with large radii of gyration about the vertical neutral axis of the section which makes a very stiff ring. It permits distribution of the metal of the ring about both the vertical and

horizontal neutral axes so that the tensional stresses of the roof plates and side wall plates may be adequately transmitted to the ring girder thus forming compressive stresses within the ring-shaped girder. Also, part of the metal of the ring-shaped girder is used as a portion of the side wall of the tank and part of such metal is used to correlate the roof plates with the side wall plates.

By the use of side wall plates curved in one direction only, as described, the fluid pressure is normal upon each integral area of the plate on the concave side thereof and the stresses at each end of an element of the plate act in the direction of curvature. Since the side wall plates of the tank are curving outwardly from the top and bottom ring and are secured tightly to the lower part of the outer flange of the upper ring and to the upper part of the lower ring at the outside edge, stresses at the upper and lower points of securement may be analyzed as follows: At the lower point of securement the resultant force of the stress in each plate acts upward and outward. This force may be resolved into two vector components, one acting in a horizontal plane and the other upwardly toward the upper ring-shaped girder. At the upper point of securement, the horizontal component acts outwardly away from center of the upper ring. The vertical component at the lower points of securement and that at the upper point of securement tend to pull these two points together, and, to make the structure rigid, the columns are located between the rings and serve to keep the points of securement apart in addition to supporting the weight of the upper ring-shaped girder, the roof and any loading thereof. The outer flange of the ring-shaped girder serves as a curved continuous beam with the columns at the supporting points, the loading being transmitted to the beam through the points of securement of the side wall plates to the outer flange of the ring-shaped girder. In order to take care of the horizontal component mentioned, I depend upon the gussets 28 extending between the upper portions of the side wall plates and the web plate 26. With the described arrangement under average loading conditions, the resultant force of the wall and roof plates pass through the neutral axis of the ring-shaped girder. Extreme loading (full tank with vapor pressure or empty tank with vapor pressure) will cause a light torque in the girder section tending to turn the ring inside out. The construction is such that the torque for the fully loaded condition is about equal, but acting in an opposite direction to that of the empty tank with vapor pressure. This torque in both the upper and lower members A and B is resisted by the trussed columns C.

I find it desirable in tanks of large capacity embodying my invention, to curve the side plates with smaller radii than the radii of the tank side wall in horizontal planes.

While I have illustrated and described one embodiment of my invention, I do not wish to be restricted thereto beyond the scope of my appended claims.

I claim:

1. A storage tank comprising an annular side wall formed of plates outwardly curved in one direction only and joined at their meeting edges against leakage, a convex roof also formed of plates outwardly curved in one direction only and joined at their meeting edges against leakage, a

supporting frame comprising a plurality of circumferentially spaced vertical columns and a horizontal radial roof truss secured to each of said columns, means disposed centrally of said roof connecting the inner ends of said trusses, and a ring-shaped girder secured to the outer ends of said trusses and to the upper ends of said columns, said side wall and said roof merging into each other, said roof being connected to said trusses, said girder being connected to said side wall and said roof at the merging juncture thereof to resist longitudinal stresses in the wall and roof plates.

2. A storage tank as defined in claim 1 in which the girder comprises inner and outer annular vertical flanges and a connecting web including diagonal struts forming a truss extending from the inner flange to the outer flange of the girder.

3. A storage tank as claimed in claim 1 in which the girder comprises inner and outer vertical flanges connected by trusses and the vertical columns each comprise vertical members connected by trusses, one of said vertical members being in alignment with and secured to the outer flange of the girder.

4. A storage tank comprising an annular side wall formed of plates outwardly curved in one direction only and joined at their meeting edges against leakage, a convex roof also formed of plates outwardly curved in one direction only and joined at their meeting edges against leakage, a supporting frame comprising a plurality of circumferentially spaced vertical columns and a horizontal radial roof truss secured to each of said columns, means disposed centrally of said roof connecting the inner ends of said trusses, and a ring-shaped I-section girder having its web horizontally disposed, said girder being secured to the outer ends of said trusses and to the upper ends of said columns, the upper terminal plates of said side wall and the peripheral plates of said roof merging into each other and secured at the merging juncture thereof to the web of said girder to resist longitudinal stresses in the wall and roof plates.

5. A storage tank as claimed in claim 4 in which the vertical columns are aligned with and secured to the radial trusses, one flange of the girder being connected to the vertical columns and the other flange of the girder being connected to the trusses.

6. A storage tank comprising an annular side wall formed of plates outwardly curved in one direction only and joined at their meeting edges against leakage, a convex roof also formed of plates outwardly curved in one direction only and joined at their meeting edges against leakage, a supporting frame comprising a plurality of circumferentially spaced vertical columns and a horizontal radial roof truss secured to each of said columns, a vertical column disposed centrally of said roof, the inner ends of said trusses being connected to said centrally disposed column, and a ring-shaped I-section girder having its web horizontally disposed, said girder being secured to the outer ends of said trusses and to the upper ends of said first-mentioned columns, the upper terminal plates of said side wall and the peripheral plates of said roof merging into each other and secured at the merging juncture thereof to the web of said girder to resist longitudinal stresses in the wall and roof plates.

7. A storage tank comprising an annular side wall formed of plates outwardly curved in one direction only and joined at their meeting edges

against leakage, a convex roof also formed of plates outwardly curved in one direction only and joined at their meeting edges against leakage, a supporting frame comprising a plurality of circumferentially spaced vertical columns and a horizontal radial roof truss secured to each of said columns, means disposed centrally of said roof connecting the inner ends of said trusses, and a ring-shaped I-section girder having its web horizontally disposed, said girder being secured to the outer ends of said trusses and to the upper ends of said columns, the upper terminal plates of said side wall and the peripheral plates of said roof merging into each other and secured at the merging juncture thereof to the web of said girder along the neutral axis of the girder to resist longitudinal stresses in the wall and roof plates.

8. A storage tank comprising a side wall, a roof, and framework carrying said roof and wall, said framework comprising a plurality of circumferentially spaced vertical columns adjacent said side wall and radial roof trusses, a ring-shaped girder connecting the outer ends of said trusses and the upper ends of said columns, said girder having an outer vertical flange, said flange being a substantially vertical extension of said side wall.

9. A tank for storage of volatile liquids under their vapor pressures, comprising a rigid frame constructed of a horizontal, reinforced-concrete, ring girder, a horizontal I-shaped steel ring girder spaced thereabove and concentric therewith, a plurality of circumferentially spaced vertical steel columns extending between said girders and securing them in assembled relation and a vertical, shell-like, cylindrical supporting member of lesser diameter and concentric with said girders, roof plates extending between said member and said steel girder and secured thereto, said roof plates being curved upwardly from their points of securement to said steel girder and to said member, radial trusses and rafters also incorporated in said frame and contributing to the support of said roof plates, said trusses being integrated with said columns by securement thereto and so constructed and arranged as to resist torques within the upper and lower girders due to loading conditions which tend to turn said girders inside out, a side wall composed of integrated side plates curved outwardly and downwardly from said roof and outwardly and upwardly from said concrete girder, said roof and side plates being curved in one direction only, said tank being additionally provided with a bottom.

10. A tank for storage of volatile liquids under their vapor pressures, comprising a rigid frame constructed of a horizontal, reinforced-concrete,

ring girder, a horizontal steel ring girder spaced thereabove and concentric therewith, a plurality of circumferentially spaced vertical steel columns extending between said girders and securing them in assembled relation and a vertical, shell-like cylindrical supporting member of lesser diameter and concentric with said girders, roof plates extending between said member and said steel girder and secured thereto, said roof plates being curved upwardly from their points of securement, radial trusses and rafters also incorporated in said frame and contributing to the support of said roof plates, said radial trusses and rafters being secured at their inner ends to said supporting member and at their outer ends to said upper girder.

11. A tank for storage of volatile liquids under their vapor pressures, comprising a rigid frame constructed of a horizontal, reinforced-concrete, ring girder, a horizontal steel ring girder spaced thereabove and concentric therewith, a plurality of circumferentially spaced vertical steel columns extending between said girders and securing them in assembled relation and a vertical-shell-like, cylindrical supporting member of lesser diameter and concentric with said girders, roof plates extending between said member and said steel girder and secured thereto, said roof plates being curved upwardly from their points of securement to said steel girder and to said member, radial trusses and rafters also incorporated in said frame and contributing to the support of said roof plates, said trusses being integrated with said columns by securement thereto and so constructed and arranged as to resist torques within the upper and lower girders due to loading conditions which tend to turn said girders inside out.
